(57) **CLAIM**

The ornamental design for a hydroponic tower, as shown and described.

DESCRIPTION

FIG. 1 is a perspective view of an embodiment of a hydroponic tower having growing slots for the growth of plants therein;

FIG. 2 is a front side elevation thereof;

FIG. 3 is a back side elevation thereof;

FIG. 4 is a top plan thereof;

FIG. 5 is a perspective view of a second embodiment of a hydroponic tower;

FIG. 6 is a front side elevation of the hydroponic tower of FIG. 5;

FIG. 7 is a perspective view of a third embodiment of a hydroponic tower;

FIG. 8 is a front side elevation of the hydroponic tower of FIG. 7;

FIG. 9 is a cut-away perspective side view of the hydroponic tower of FIG. 1 taken from FIG. 7;

FIG. 10 is a cut-away rear view of the hydroponic tower of FIG. 1 taken from FIG. 3; and,

FIG. 11 is a front elevation of the hydroponic tower of FIG. 1, showing an embodiment of hanging from a mounting bar, and plant growth in the growing slots thereof.

The broken lines shown in the drawings represent environment only and form no part of the claimed design.

1 Claim, 8 Drawing Sheets
